US0D1100735S

(12) **United States Design Patent** (10) **Patent No.:** **US D1,100,735 S**
(45) **Date of Patent:** ** *Nov. 4, 2025

(54) **SHELF FOR PLANT CULTIVATION**

(71) Applicant: **CGIP, Inc.**, Coral Springs, FL (US)

(72) Inventors: **Michael Robert Tinsley**, Coral Springs, FL (US); **Frederick Ellingsworth Morgan**, Coral Springs, FL (US); **Douglas Allen Drew**, Leesburg, FL (US)

(73) Assignee: **CGIP, Inc.**, Coral Springs, FL (US)

(*) Notice: This patent is subject to a terminal disclaimer.

(**) Term: **15 Years**

(21) Appl. No.: **29/856,141**

(22) Filed: **Oct. 11, 2022**

(51) LOC (15) Cl. **06-06**

(57) **CLAIM**

The ornamental design for a shelf for plant cultivation as shown.

DESCRIPTION

FIG. 1 is perspective view of the invention;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines shown in the drawings illustrate parts of the shelf for plant cultivation that forms no part of the claimed design.
